FUSE PLATE STRUCTURE

Eugene J. Fix and Benjamin B. Patton,
Philadelphia, Pa.

Application September 20, 1941, Serial No. 411,626

1 Claim. (Cl. 161—1)

(Granted under the act of March 3, 1883, as
amended April 30, 1928; 370 O. G. 757)

1

The invention described herein may be manufactured and used by or for the Government for governmental purposes, without the payment to us of any royalty thereon.

This invention relates to a laminated composite plate support for the clockwork train of a mechanical time fuse and constitutes a continuation in part of our co-pending application, Serial No. 249,260, filed Jan. 4, 1939, now abandoned.

It is a principal object of the invention to produce a mechanical fuse having individual plate units of the conventional laminated plate support for the clockwork train formed of a composite structure for the purpose of facilitating mass production thereof.

In view of the tremendous forces of "set-back" arising in firing a shell of such caliber as would be provided with a mechanical time fuse it has heretofore been the practice in the art to make the plate units of a laminated clockwork train support for a mechanical time fuse of the type shown in U. S. Patent No. 1,927,746 of as great thickness as was consistent with an arrangement of the plates that could be designed to receive and support the gears, pinions, arbors and other essential elements of the clockwork train and fuse. The purpose of course in forming the individual plates of the support of as great thickness as possible was to reduce the total number of plates in the support to an absolute minimum whereby the possibility of the plates being squeezed together in more intimate contact under the stress of firing to an extent sufficient to bind or jam the elements of the clockwork train would also be reduced to a minimum. A clockwork train support for a fuse formed in this conventional manner functions satisfactorily in service. However, difficulties are presented in fabrication since the plates are of such thickness and the number of openings formed therein to provide bearings and encase the elements of the clockwork train are so numerous and disposed on such closely spaced centers as to prohibit pierce punching of the individual plates because of the high breakage of the pierce punches or altogether preclude a pierce punching operation because of the close spacing of the openings, it being found that in plates of conventional thickness an opening cannot be placed closer than 35% of the diameter of the punch to the edge of or another opening in such conventional plate without destroying the web between said opening and edge of the plate or adjacent opening as the case might be. Further, inasmuch as pierce punching on plates of conventional thickness is precluded as a practical

2

operation the form of the openings to provide bearings for the arbors, supports for the pinions and gears, and relieved areas for receiving other elements of the clockwork train require the several operations of drilling, counterboring, routing and milling and the drilling cannot be accomplished on one plate in one operation by gang drills as the centers of the openings preclude spacing the drills of a gang drill on such closely spaced centers; consequently, errors creep in the spacing of openings as the plate is passed from drill station to drill station due to the fact that the work (plate) is not secured in the same relative position at each drill station. This results in non-identical performance of the fuses because of the variation in friction in the clockwork trains thereof arising from the variable bearing relations of the arbors, etc., to their bearing openings in the plates disposed on said erroneous spacing of centers.

Another object of this invention is to provide a composite plate adapted to be formed into a laminated fuse clockwork train of the conventional type which will obviate all of the aforesaid difficulties and which may be fabricated by the usual blanking operation, and a die punching and shaving operation.

Still another object of the invention is to provide a plate so compositely formed that each component thereof may have the openings therein formed by a single die punching operation.

The specific nature of the invention as well as other objects and advantages thereof will clearly appear from a description of a preferred embodiment as shown in the accompanying drawings in which:

Fig. 1 is an elevational view of a conventional fuse clockwork train support;

Fig. 2 is an elevational view of a fuse clockwork train support fabricated in accordance with this invention;

Fig. 3 is a plan view of a composite plate comprised of the complemental plate components of Figs. 4 and 5;

Fig. 4 is a plan view of one of the plate components of the composite plate shown in Fig. 3;

Fig. 5 is a plan view of a plate component complemental to component shown in Fig. 4 utilized in fabricating the composite plate of Fig. 3;

Fig. 6 is a sectional view taken upon the section line 6—6 of Fig. 3, and

Fig. 7 is a sectional view taken upon the section line 7—7 of Fig. 3.

Referring now to the drawings and more especially to Fig. 2 there is shown a clockwork train

support for a mechanical fuse in accordance with this invention comprised of laminated composite plates 10, 11, 12, 13 and the usual filler and top plates 14, 15, and 16 which for purposes of convenience may be compared with the corresponding plates 10', 11', 12', 13', 14', 15' and 16' of a conventional clockwork train support as shown in Fig. 1.

By arranging the plates 10', 11', 12', and 13' as composite structures as shown in Fig. 2 such plate members of the conventional clockwork support for a mechanical fuse as have heretofore precluded drilling or punching of the necessary gear, pinion, arbor and other openings for elements of the clockwork train and fuse in one operational step have been so arranged that the components of the corresponding composite plates 10, 11, 12, and 13 of our invention may be pierce punched in a single operation and thereafter assembled into composite plates having openings of various depths, configurations and arranged in different patterns to serve as bearings for pinions, gears, arbors and clearances for other elements of the clockwork train and fuse, thereby greatly facilitating production by eliminating the several steps of drilling, counterboring, milling and routing to accomplish the same end in the conventional comparatively thick unitary plates.

As an illustration of how the composite plates of our invention are formed reference is made to the composite plate shown in Fig. 3 which may be considered as plate 11 shown in Fig. 2 and which will serve to illustrate the principles involved in the fabrication of any of the other composite plates 10, 12 or 13 of our invention. The composite plate 11 is comprised of a plurality of generally circular complementary component members, which in the specific instance of composite plate 11 is two components indicated at A and B in Figs. 4 and 4, respectively, although it will be understood that the number of components in any particular composite plate will vary with the number and disposition of the openings in that plate.

The desired pattern or arrangement of openings in composite plate 11 is clearly shown in Fig. 3 and the individual openings are indicated at 17, 18, 19, 20, 21, 22, 23, 24, 25, 26, 27, 28, 29, 30, 31 and 32. As these openings are so closely spaced as to preclude drilling of the plate in one operation and as a unitary plate of the same thickness as the composite plate 11, that is plate 11 of Fig. 1, is too thick to allow pierce punching since certain of the openings are closer than 35% of the diameter of the punch to the edge of the plate or another opening we have selected two component members A and B of such thicknesses as to be adapted to pierce punching and collectively of the same thickness as plate 11. The component members A and B are then pierce punched in one operation with the necessary gear, pinion and arbor bearing openings as well as openings and peripheral recesses or notches collectively referred to as openings, to receive other elements of the clockwork train and fuse so that when shaved and assembled in superim-

posed relation the individual openings of the two component members A and B will be complementary in forming the final desired arrangement or pattern of openings 17-32 in the composite plate 11. The arrangement or pattern of openings is accomplished in the case of composite plate 11 by pierce punching the openings, apertures, or peripheral recesses 17', 18', 19', 21', 22', 23', 24', 25', 27', 28', 29', 30', 31' and 32' in component member A and openings 17'', 18'', 19'', 21'', 22'', 23'', 24'', 25'', 27'', 28'', 29'', 30'', 31'', 32'', 20 and 26 in component member B after which the component members A and B are assembled in superimposed contacting relation with the openings 17-17', 18'-18'', 19'-19'', 21'-21'', 22'-22'', 23'-23'', 24'-24'', 25'-25'', 27'-27'', 28'-28'', 29'-29'', 30'-30'', 31'-31'' and 32'-32'' disposed in complementary relation to form the openings 17, 18, 19, 21, 22, 23, 24, 25, 27, 28, 29, 30, 31 and 32 of the composite plate. The openings 20, 26 of component member B have no complementary counterparts in component member B and it will of course be understood that a greater or less number of openings similar to the openings 20, 26 may be formed in the complementary component members of the other composite plates 10, 12 and 13.

The component members of the composite plates are retained in assembled relation by dowel pins or in any other suitable manner, such as by threaded fasteners which extend through all the plates of the support as is well known in the art.

The plates 14, 15 and 16 of the fuse are either formed of a different metal than the metal of the composite plates or have so few and widely spaced openings that they can be either pierce punched or drilled in one operation.

Having now described our invention in accordance with a present preferred embodiment we claim:

In a mechanical time fuse, a clock-train support having openings for the reception of clockwork fuse components, in combination, a plurality of composite plates each component part of each composite plate being of a thickness that permits pierce punching of a pattern of openings which are closer than 35% of the diameter of a punch to the edge of the nearest opening, whereby each component part of each composite plate may be prepunched in one operative step, and means for retaining the component members of each composite plate in superimposed contacting relation with the patterns of the openings arranged in complementary relation.
